BY *G. M. Reed*
ATTORNEY

UNITED STATES PATENT OFFICE.

LUCENA M. MORDEN, OF WATERBURY, CONNECTICUT.

LOOSE-LEAF BINDER.

1,037,292.

Specification of Letters Patent. Patented Sept. 3, 1912.

Application filed March 31, 1911. Serial No. 618,058.

To all whom it may concern:

Be it known that I, LUCENA M. MORDEN, a citizen of the United States, residing at Waterbury, in the county of New Haven 5 and State of Connecticut, have invented certain new and useful Improvements in Loose-Leaf Binders, of which the following is a specification.

This invention relates to loose leaf binders, the object of the invention being the production of a binder of this class capable of holding independent sets of leaves so that when the binder or the book is opened the leaves will lie flat.

15 A further object of the invention is the provision of an improved binder of this character extremely simple in its construction and in which the holding rings may be shifted or adjusted so as to properly position the same to accommodate leaves which may be improperly perforated.

20 A further object of the invention is the provision of an improved binder of the class described specially constructed to permit the same to be used with slotted leaves, without the necessity of complicating the device by providing means for opening and closing the rings.

25 A further object of the invention is the provision of an improved binder of the character described having what is termed herein solid, integral or one-piece rings as contra-distinguished from those forms of rings known as separable rings or prongs, and which rings are supported by a flexible member, whereby the leaves of the book will be carried in independent sets.

30 In the drawings accompanying and forming part of this specification, Figure 1 is a perspective view illustrating one of these improved binders; Fig. 2 is a perspective detail view illustrating one of the sets of rings; Fig. 3 is a perspective view of one of the rings;—Fig. 4 is a view of one of the 35 slotted sheets; and Fig. 5 illustrates a portion of the flexible back member.

Similar characters of reference indicate corresponding parts throughout the drawings.

40 In one embodiment herein shown and described, the binder comprises covers 2 connected by a suitable flexible back 3 to permit the covers to be opened and closed. Inside of this back is a supplemental back portion

4 of some suitable flexible material, and connected to this back portion are a series of longitudinally extending members 5, shown herein as metal strips each so folded as to clamp a portion of the flexible back therebetween. Each of these metal strips forms 55 a guideway for the rings 7, and the several metal strips are located at predetermined distances apart. Instead of the metal strips obviously the flexible back could be formed in ridges or ribs, especially if some suitable 60 reinforcing material, as a wire or other structure, is located therein to give it sufficient rigidity and stability. In the present instance the metal strips are shown as of dove-tail form for the reception of the solid 65 rings 7, which are split to receive the guide strip and grip the same with a spring action. It will be observed that the rings shown herein have considerable width, so that each has a wide bearing engagement 70 with its guide and is therefore permanently maintained upright against sidewise swinging movement. By this construction it will be observed that the rings may be adjusted or shifted longitudinally of the strip to 75 properly position them according to the distances between the slots of the leaves 10, which slots are shown as T-shaped slots 11, whereby they may be readily inserted on to the rings without the necessity of dividing 80 or separating the rings as heretofore. Each guide carries a plurality of rings, and the rings of one guide may be located in any desired position relatively to the rings of its companion guide or bar, each set or row of 85 rings carrying a predetermined number of 90 sheets so that each set of sheets is carried by its own set of rings and independently of the companion sets of sheets. By this construction I am able to provide a binder in 95 which the sheets or pages of the book may be readily opened so as to lie flat, while at the same time the structure is very much simplified in its construction and therefore very much less expensive to manufacture, as 100 well as much stronger and more durable in use and much more quickly and easily operated than binders heretofore constructed, while the leaves can be removed instantly, since it is unnecessary to manipulate the 105 rings so as to open or close the same.

As hereinbefore stated, the flexible back member could be formed in ridges or ribs,

especially if some suitable reinforcing material such as wire or otherwise is located therein to give it sufficient rigidity and stability, this being necessary when the back member is made of cloth or leather, but when made of metal, as in the embodiment shown in Fig. 5, these ribs or ridges will constitute the guides without the necessity of any reinforcing material whatever. In 10 Fig. 5 this flexible back member 4' is shown made of metal comprising a series of hinged plates or members 15 having integral portions thereof bent upward to form longitudinally extending bars, ribs or projections 15 16 for the reception of the rings. By making the back member in the form shown it can be readily expanded or decreased merely by adding or removing one or more of the hinged plates thereby to increase or 20 decrease the size of the book.

I claim as my invention:

1. A loose leaf binder comprising a flexible member having a plurality of longitudinally extending guides each constructed to 25 hold its rings against rotation and transverse movement relatively to such guide, and a plurality of integral non-rotatable rings each split at its underside to directly grip its guide, whereby said rings are permanently held by such guide against rotatable and transverse movement.
2. A loose leaf binder comprising a flexible member having a plurality of longitudinally extending guides and a plurality of 35 integral rings carried by each of said guides and each split at its underside to grip its guide and shiftable along said guide.
3. A loose leaf binder comprising a flexible member having a plurality of longitudinally extending guides each constructed to 40 hold its rings against rotation and transverse movement relatively to such guide, and a plurality of integral non-rotatable rings each split at its underside to directly grip its guide with a spring action and adapted for the reception of slotted leaves without the opening of said rings and each having a wide bearing surface upon its guide whereby sidewise swinging movement 45 50 of the ring is prevented and such ring permanently maintained upright on its guide.
4. A loose leaf binder comprising a flexible member having a plurality of longitudinally extending guides each carrying a plurality of integral rings each split at its underside directly to engage its guide with a spring action and shiftable along its guide, and leaves slotted for insertion onto said rings without the opening of said rings.
5. A loose leaf binder comprising a flexible member having a longitudinally extending guide constructed to hold its rings 60 against rotation and transverse movement

relatively to such guide, and a plurality of integral non-rotatable rings each split at its underside to directly engage its guide, each of said rings having a wide bearing surface upon its guide whereby sidewise swinging movement of the ring is prevented and such ring permanently maintained upright on its guide.

6. A loose leaf binder comprising a flexible member having a plurality of longitudinally extending dovetail-shaped guides each carrying a plurality of integral rings each split at its underside directly to engage its guide with a spring action and shiftable along the same.

7. A loose leaf binder comprising a flexible member made up of a plurality of hinged members having longitudinally extending guides each carrying a plurality of rings.

8. A loose leaf binder comprising a flexible member made up of a plurality of hinged members having longitudinally extending guides each carrying a plurality of integral rings.

9. A loose leaf binder comprising a flexible member made up of a plurality of hinged members having integral projections forming longitudinally extending guides each carrying a plurality of integral rings.

10. A loose leaf binder comprising a flexible member made up of a plurality of hinged members having integral projections forming longitudinally extending guides each carrying a plurality of integral rings shiftable along said guides.

11. A loose leaf binder comprising a flexible member made up of a plurality of hinged members having integral projections forming longitudinally extending guides each carrying a plurality of integral rings shiftable along said guides, and leaves slotted for insertion on to said rings without the opening of said rings.

12. A loose leaf binder comprising a flexible metal member made up of a plurality of hinged plates whereby the structure may be readily expanded or decreased in size by the addition or detachment of one or more of such members, said flexible member having a plurality of longitudinally extending guides, and rings carried by said guides.

13. A loose leaf binder comprising a flexible metal member made up of a plurality of hinged plates whereby the structure may be readily expanded or decreased in size by the addition or detachment of one or more of such members, said flexible member having a plurality of longitudinally extending guides, and integral rings carried by said guides for the reception of slotted leaves without the opening of said rings.

14. A loose leaf binder having a flexible back member made up of a plurality of

hinged plates whereby the structure may be readily expanded or decreased in size by the addition or detachment of one or more of such plates each of said plates having means extending lengthwise of the plate and projecting above the surface thereof for the reception of integral rings.

Signed at 1821 Park Row Building, New York, N. Y., this 28th day of March, 1911.
